DESIGN FOR A DRESS

Henry Schultz, New York, N. Y.

Application December 20, 1938, Serial No. 81,884

Term of patent 3½ years

To all whom it may concern:

Be it known that I, Henry Schultz, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged view of the sleeve as seen from the side illustrating the embroidery.

The characteristic feature of my design resides in the combination on the specific dress disclosed of the specific embroidery on the sleeve portions as shown.

I claim:

The ornamental design for a dress, substantially as shown and described.

HENRY SCHULTZ.
